UNITED STATES PATENT OFFICE.

ERNEST HIGGINS, OF GLOUCESTER, ENGLAND.

COLLAR AND LIKE ARTICLE OF WEARING APPAREL.

Application filed July 2, 1925, Serial No. 41,125, and in Great Britain May 28, 1925.

This invention relates to collars of the double or single fold type and in particular to the starched or stiff variety although equally applicable to soft collars.

With conventional collars it is nearly always a matter of difficulty to prevent the knot of the tie from slipping down in the front and various devices have been proposed for remedying this defect such as detachable clips adapted to support the tie between the folds of the collar.

As far as I am aware not any of these devices have met with any great success, as, being detachable, they require affixing in position each time a collar is put on and furthermore they are very liable to get lost.

The object of the present invention is to provide means of a simple kind which will act efficiently to maintain the tie in the correct position and which will obviate the above mentioned defects.

I effect this object in the present invention by making the tie supporting means a permanent fixture on the collar.

The invention may therefore be said to consist broadly of a collar and like article of wearing apparel having at least two tabs or their equivalent permanently attached thereto in such a manner as to serve as a support for a tie.

The main object of the invention is to provide a collar and the like article of wearing apparel wherein the tabs are positioned adjacent to each of the usual locks so as to afford a support for the tie at the front.

Another object of the invention is to provide a collar of this nature wherein the tabs are permanently attached by their lower portions to the collar by stitching so as to form upwardly extending loops for the support of a tie.

Another object of the invention is to provide a collar of this nature having at least two tabs composed of the same material as the collar so as to be laundered with the collar and afford a support for the tie at the front.

Another object of the invention is to have the tabs attached to the collar with the lower edges pointing upwards, the main portion of each tab being folded adjacent to the attached portion so as to reside normally parallel thereto and form a loop behind each of which the tie is adapted to be positioned.

Another object of the invention is to have each of the tabs formed with an additional

fold whereby the main portion of the tab is capable of residing parallel to but spaced from the portion which is attached to the collar so as to freely accommodate the thickness of a positioned tie.

Still another object of the invention is to provide a collar of this nature having at least two tabs each of which is formed with two parallel folds so as to form three portions, the inner portion being permanently attached to the collar and the outer or main portion residing normally parallel to it, the intermediate portion serving to permit the outer or main portion to move towards or away from the collar to accommodate ties of different thickness between such main portion and the collar.

The invention also consists of a collar and like article of wearing apparel having tabs constructed and arranged substantially as hereinafter described with reference to the accompanying drawings.

The term tab as used in this specification is intended to include, in its broadest sense, any member with or without bending creases and of any material and shape which is capable of being permanently attached to the collar and affording support to the tie.

In order that the invention may be clearly understood an embodiment of the same as applied to a double fold collar of the stiff or starched variety will now be described, by way of example, by aid of the accompanying drawings in which:—

Fig. 1 is a view of the inside of the collar showing the tie when first placed in position behind the tabs.

Fig. 2 is a perspective view of the collar and the tie in the position ready for affixing around the neck of the wearer.

Fig. 3 is a perspective view of the collar and tie when affixed.

Fig. 4 is an enlarged detail in perspective of one of the tabs showing the same turned down to expose the inner portion.

Fig. 5 is a section through the collar and one of the tabs to an enlarged scale showing clearly the positions of the two parallel bending creases.

In the drawings A and B represent the inner and outer folds of the collar, and C the tabs. In the example illustrated each tab is formed with two parallel natural bending creases D and E by being stitched which are spaced apart so as to divide each tab into three portions, an inner portion F,

an intermediate portion G and an outer or main portion H. These tabs are permanently attached by their inner portions F to the outside of the inner fold A of the collar 5 adjacent each of the usual locks I so as to afford support for the knot J of the tie. The tabs may most conveniently be attached to the collar by stitching as at K and are preferably made of the same material as the 10 collar with which they are laundered as occasion demands.

The intermediate portion G of each tab is permitted to assume any position between the horizontal and the vertical according to 15 the distance from the inner fold of the collar the main portion H is required to be to accommodate the thickness of a particular tie which is placed in position from above and when in position is supported by the intermediate portions of the tabs and between 20 their main portions H and the inner fold of the collar.

In the example illustrated the inner portion F of each tab is stitched to the collar 25 with its outer edge uppermost but if desired such portion may be affixed in position with such edge pointing downwards.

If desired a third tab may be similarly provided in the centre of the collar band so 30 as to afford support for the tie at the back. This additional tab is however not an essential and may be omitted without departing from the present invention. Similarly more than three tabs may be provided if desired.

35 Tie supporting means according to this invention may be made in any suitable material for use with starched linen, zephyr,

print, poplin or other collars. When used with soft collar tabs composed of either stiff or soft material of the same kind as 40 used for the collar may be employed.

It will be seen that by means of the present invention I have provided simple and inexpensive means which will ensure adequate support for the tie at the front so as 45 to prevent the tie band from slipping down both when affixing the collar and when in wear and means which, in the case of double fold collars, are in no way visible thus maintaining the conventional appearance of the 50 collar.

I claim—

A collar having at least two tabs permanently attached thereto adjacent to each of the usual locks, each tab being formed with 55 two parallel natural folds by being stitched so as to form three portions, the inner portion being permanently attached to the collar with its edge pointing upwards and the outer portion residing normally parallel to 60 it, the intermediate portion attached to the collar at the lower edge only and serving to permit the outer portion to move towards or away from the collar to accommodate ties of different thicknesses between such outer 65 portion and the collar, the tabs being essentially secured to the collar at a distance above its bottom edge so as to maintain the knot of the tie in the correct position at the front.

In testimony whereof I have affixed my signature.

ERNEST HIGGINS.
